UNITED STATES PATENT OFFICE.

CLEMENT G. MILLER, OF KANSAS CITY, MISSOURI.

ARTIFICIAL TEETH.

Application filed September 18, 1925. Serial No. 57,152.

My invention relates to artificial teeth and metal parts designed for use in dental bridge work.

In methods now in use for abridging spaces between abutments with artificial teeth, gold teeth are used or porcelain and gold or noble metal alloy parts are used. The metal parts of the teeth are soldered to the crowns, inlays or attachments used for the abutments, the porcelain being attached by metal pins baked into the porcelain or by holes passing through or part way through the porcelain toward the occlusal surface; metal pins fit in the holes and connect to a metal base or occlusal surface. In other cases, the metal supports the lingual, mesial and distal sides of the porcelain teeth. When metal pins are not baked into the porcelain, cement is used to hold the porcelain and gold together.

My invention consists of porcelain artificial teeth with metal parts that fit in the mesial and distal sides only, and presents an artificial restoration with porcelain lingual, occlusal, buccal, labial, and cervical portions similar in shape to the natural teeth. The porcelain is countersunk at the mesial and distal contact sections and beyond these countersunk parts one or more holes penetrate into the tooth mesio-distally to allow for metal connections.

The restoration can be constructed with much saving in cost, and fills many requirements of the dental profession.

The construction, combination and arrangement of parts as described herein and claimed as illustrated in the accompanying drawings:—

Fig. 1 is a view illustrating a posterior upper bridge showing the front and part of occlusal surface.

Fig. 2 represents metal devices in position on artificial molar.

Fig. 3 represents porcelain artificial molar and metal devices ready to be placed into position.

Fig. 4 represents porcelain artificial molar showing buccal and distal sides and scheme of construction of tooth.

Fig. 5 is a front view illustrating anterior upper bridge.

Fig. 6 shows side view of anterior porcelain artificial tooth with countersunk triangular shape in the side.

Fig. 7 represents an upper central incisor with the metal retainers in position in the mesial and distal sides of the tooth.

In the following description of my invention: A to A¹ inclusive represent metal abutments which can either be cast gold inlays or gold crowns. B to B¹ inclusive represent the porcelain artificial teeth used between the abutments and can either be an incisor, cuspid, bicuspid or molar tooth. D and D¹ represent metal retaining devices with projecting pins E and E¹. The devices are triangular in shape and of suitable thickness to act as a shoulder to fit under the countersunk ledge G, made in the side of the tooth. The pins projecting from the triangular shaped metal are of suitable size to complete the retentive ability of the device and to bear the stress of occlusion on the tooth held by the devices.

D is shown soldered with the flat side to the distal of A; one side of the triangle toward the occlusal, pins E projecting distally. Another D is soldered to the mesial of A¹, in a similar position, but with the pins projecting mesially. Two D's are shown soldered together, pins projecting mesially from one and distally from the other. The D's are shown in correct position and projecting in similar size and shaped holes and countersunk parts in the mesial and distal sides of B and B¹. The bridge is made firm when the porcelain teeth are cemented to the metal parts.

C shows a continuation of the holes through the center of the tooth in which pins E fit. It can be seen that the two D's soldered together form the union that holds B and B¹.

Q shows part sectional view of tooth in Fig. 3.

G represents a section of the countersunk part shaped to receive D.

F shows the thickness of D, compared to the size of the tooth.

Pins E and E¹ are of suitable size and strength to hold firmly when cemented in C.

D¹ represents metal retainers for anterior and cuspid teeth one angle of the device points towards the incisal of the tooth; the projecting pins one above the other and projecting into the porcelain teeth mesio-distally. Four D¹'s are shown in position on a bridge illustrated in Figure 5. The side view of B¹ in Figure 6, shows G², the different position of the triangular countersunk part for anterior teeth and holes C¹ in different position to those shown in Figures 1, 2, 3 and 4 for posterior teeth.

The different positions of D¹ for incisor teeth, to D for the posterior teeth, is illustrated in Fig. 4, and Fig. 6, with an angle

toward the incisal and the pins, one above the other. The pins of D are level with each other.

From the illustrations it can be seen, I have 5 described my patent as triangular shaped metal parts, with projecting pins which fit into the mesial and distal sides of teeth prepared to receive same, and the metal parts that slide into the mesial and distal sides of 10 prepared teeth.

I do not limit myself to any particular shaped metal parts, or to using pins in a certain position on those parts; the idea is to hold the porcelain teeth with metal parts 15 which fit in the mesial and distal sides of them, and to use a modification of the shape in any manner that may be deemed best for carrying out the invention, without, however, departing from the real spirit thereof.

20 Having thus described the nature and objects of my invention, what I claim as new and desire to secure by Letters Patent, is—

1. An artificial tooth having an angularly shaped side socket and bores extending inwardly from the socket, and a metal retainer 25 comprising a body portion seatable in said

socket and spaced pin elements integral with the body portion projectable into said bores, said body portion having a flat face for soldering to an abutment.

2. In combination, artificial teeth having 30 characteristic sockets in their sides, and parallel bores penetrating the teeth from the socket floors, and metallic units having integral portions receivable by the sockets and the bores and portions extending laterally from the sockets for attachment to adjacent teeth for supporting said artificial teeth directly from adjacent teeth.

3. In a dental bridge, means for supporting 35 adjacent artificial teeth between abutments, comprising triangular shaped metal elements, each having a plurality of pins projecting from one side, the sides of the elements opposite the pins being adapted to be 40 soldered together, and the artificial teeth being provided with recesses to receive the metal elements.

In witness whereof, I have hereunto set my hand.

CLEMENT G. MILLER.
